CLAIM

The ornamental design for a display screen of a respiratory support apparatus or portion thereof with graphical user interface, as shown and described.

DESCRIPTION

FIG. 1 is a front view of a display screen of a respiratory support apparatus or portion thereof with graphical user interface showing our new design.

FIG. 2 is a front view of a display screen of a respiratory support apparatus or portion thereof with graphical user interface in accordance with a second embodiment.

FIG. 3 is a front view of a display screen of a respiratory support apparatus or portion thereof with graphical user interface in accordance with a third embodiment.

FIG. 4 is a front view of a display screen of a respiratory support apparatus or portion thereof with graphical user interface in accordance with a fourth embodiment.

FIG. 5 is a front view of a display screen of a respiratory support apparatus or portion thereof with graphical user interface in accordance with a fifth embodiment.

FIG. 6 is a front view of a display screen of a respiratory support apparatus or portion thereof with graphical user interface in accordance with a sixth embodiment.

FIG. 7 is a front view of a display screen of a respiratory support apparatus or portion thereof with graphical user interface in accordance with a seventh embodiment.

FIG. 8 is a front view of a display screen of a respiratory support apparatus or portion thereof with graphical user interface in accordance with an eighth embodiment; and,

FIG. 9 is a front view of a display screen of a respiratory support apparatus or portion thereof with graphical user interface in accordance with a ninth embodiment.

The broken lines, including those showing a display screen or portion thereof and those depicting portions of a graphical user interface, form no part of the claimed design. The ornamental design for a display screen or portion thereof with a graphical user interface, shown in any of FIGS. 1-9,

(Continued)

may be within a graphical user interface of a respiratory support apparatus, a computing device, or a mobile computing device.
